UNITED STATES PATENT OFFICE.

STANLEY B. KENT, OF NEW YORK, N. Y., ASSIGNOR TO WESTERN ELECTRIC COMPANY,
OF NEW YORK, N. Y., A CORPORATION OF ILLINOIS.

INDUCTANCE-COIL FOR TELEPHONE-LINES.

1,158,810.

Specification of Letters Patent.

Patented Nov. 2, 1915.

Application filed September 12, 1914. Serial No. 861,393.

To all whom it may concern:

Be it known that I, STANLEY B. KENT, a citizen of the United States, residing at New York, in the county of New York and State 5 of New York, have invented certain new and useful Improvements in Inductance-Coils for Telephone-Lines, of which the following is a full, clear, concise, and exact description.

10 This invention relates to telephone lines, and its objects are to simplify the construction, to lessen the cost of manufacture, and to increase the efficiency of inductance coils therefor and particularly of a certain type 15 of loading coil having discontinuous cores.

It has been found of great advantage to construct the cores of loading coils with air-gaps, thus providing demagnetizing poles which act to reduce the amount of residual 20 magnetism in the iron core when the line windings have been subjected to lightning or other strong foreign currents. Without such air-gaps, the inductances of the coil winding will vary from time to time, causing 25 "singing" of the repeaters, or when the line is subjected to superposed telegraph currents the telephonic transmission qualities of the line will be seriously impaired. In fact, an enormous gain in telephonic 30 transmission is possible by combining amplifying repeaters with loading coils having discontinuous or air-gap cores, and a substantial improvement is secured in the quality 35 of telephonic transmission in the case of telegraph working on telephone lines loaded with such coils.

In a phantom telephone line system, the phantom circuit loading coil usually requires four sets of windings, one for each of 40 the four line conductors of the system, each line winding including the outer sectional winding on one quadrant of the core connected in series with the inner sectional winding on the opposite core quadrant. It 45 has been proposed to build such loading coils with cores divided into four sections by four air-gaps located between the winding sections, thus producing a discontinuous core wholly symmetrical with respect to the 50 windings. Such symmetry was required on

account of the necessity of balancing the admittances between the several core windings to avoid crosstalk between the different circuits of the system. Four air-gaps, however, are undesirable from a manufacturing 55 standpoint as the cutting of so many gaps and the assembling of the parts after cutting, seriously increases the difficulties and the cost of manufacture, and reduces the efficiency of the coil.

It is in respect to phantom coils of this general type that the present invention is particularly applicable, and the matter of reducing the number of air-gaps without introducing an unbalanced condition that 60 would cause crosstalk, which is the particular purpose of this invention, is met in accordance therewith by electrically connecting the separated core sections. Instead of four core sections, the coil may thus be constructed with only two sections separated 65 preferably by diametrically opposite air-gaps located between adjacent coil windings, a conductor being provided to join the sections electrically. This conductor is preferably 70 a non-magnetic metal pin or a plurality of pins pointed at each end and piercing one or both of the core separators and the adjacent core sections.

The invention will be more fully understood by reference to the accompanying drawing, in which—

Figure 1 illustrates the core of a phantom circuit loading coil partly insulated; Fig. 2, the same fitted with winding heads and 85 separators, and showing the inner winding on one section completed. Figs. 3 and 4, the same when wound; Fig. 5, a machine for cutting gaps in the core; Fig. 6, a fragment of the coil in section showing one gap spacer 90 and conducting pins piercing the core sections; Fig. 7, a perspective view of the same spacer and four pins; Fig. 8, a simple diagram of a phantom line system showing the general relation of the coil windings to a 95 core having two air-gaps. In this figure the core is developed into a straight line instead of being shown in its natural toroidal form; and Figs. 9 and 10 are views of the completed coil, the latter being partly in section. 100

Referring first to Fig. 8: The core of a phantom loading coil is shown separated into two sections 1 and 2, by air-gaps 3 and 4. Eight winding sections 5 to 12 inclusive are indicated in the positions they occupy generally to the core sections. Each of the four line conductors 13 to 16 of the phantom system includes an outer sectional winding, say 5, on one core quadrant in series with an inner sectional winding, 6, on the opposite core quadrant. The line conductors 13 and 14 comprise one of the side circuits extending between telephone stations 17 and 18; conductors 15 and 16 constitute another side circuit extending between stations 19 and 20, and the four conductors together make up the third or phantom circuit extending between stations 21 and 22. The two core sections are electrically connected by one or more non-magnetic conducting pins 23. If the conducting path through this pin from core section 1 to core section 2 were not provided, there would be a path for crosstalk between the side circuit 13, 14 and the side circuit 15, 16 on account of the capacity due to the close proximity of the inner windings 8, 11 and 6, 9 and the core sections 1 and 2, respectively, and thus an unbalanced condition resulting from the division of the core into a less number of sections than the winding sections. To explain this unbalance, let it be assumed that telephonic conversation is being carried on from station 17 to station 18, and that the pin 23 is not present, cross-talk would take place over the following circuit: From conductor 13, through outer winding 5 to inner winding 6, thence to the core section 2 and to the inner winding 11, thence through the repeating coil windings 24 and 25 in parallel to conductor 15, thence by way of inner winding 9, core section 1 and inner winding 8, to the opposite conductor 14 of the originating circuit. By electrically connecting the core sections 1 and 2, this by-path for crosstalk is short-circuited so that the only effect is a slight and negligible shunting of the telephonic currents generated in either of the side circuits.

The remaining figures of the drawing illustrate the construction of the preferred embodiment of a phantom loading coil according to the invention. In manufacturing the coil, a toroidal core 1 is first formed by winding a coil of fine iron wire. This core is then insulated by strips of material 2 and prepared for winding by placing at four equidistant points the winding heads 28 and separators 29. After the several windings are placed on the core, two of the separators 29, at diametrically opposite points on the core, are removed and the coil separated into two semi-circular sections in the machine shown in Fig. 5. This machine has a table 30 to which the coil is clamped. A pair of

thin steel guides 31 are placed over the core 65 in the position occupied by the separators 29, and the gaps are cut by the band-saw 32 working between the guides. After the cutting operation the two sections of the coil are brought together against gap spacers 33, 70 one at least of which has conducting pins 23 held therein. These pins pierce the adjacent core sections between the iron wires thereof. The sections are held together with the gap spacers therebetween by a clamp 34, which is 75 preferably of metal having high electrical resistance characteristics to avoid eddy current losses from stray magnetic forces. The two parts of the clamp 34 are drawn together and about the coil by bolts 35. The 80 ends 36 of the windings are brought to the outside of the coil as shown, and the coil is bound with heavy cord 37 to protect the windings and insulation.

While the invention is especially applicable to phantom loading coils having a lesser number of air-gaps than core winding sections, it is not intended to be limited to such coils, inasmuch as the joining by electrical conductors of separated core sections 90 may be found useful in other types of loading coils and also in coils for other purposes.

What is claimed is:

1. An inductance coil comprising a core formed in separated sections, and a conductor of non-magnetic material joining said sections electrically. 95
2. An inductance coil comprising a core formed in separated sections, and a spacer between said sections composed partly of 106 non-conducting material and partly of conducting material.
3. An inductance coil comprising a core formed in separated sections, sheets of non-conducting material between said sections, 105 and a conductor supported by one of said sheets and joining said core sections electrically.
4. An inductance coil comprising a core formed in separated sections, non-conducting spacers between said sections, and a conducting pin extending through one of said spacers and electrically contacting with said core sections. 110
5. An inductance coil comprising a core 115 formed in separated sections, spacers of non-conducting sheet material between said sections, a plurality of conducting pins supported by at least one of said spacers and electrically contacting with said core sections. 120
6. An inductance coil comprising a core of magnetizable wire, said core being formed in separated sections, spacers between said sections, and a conducting pin pointed at 125 each end piercing one of said spacers and the adjacent core sections.
7. In a phantom loading coil the combina-

tion with a core and line windings distributed on a plurality of sections thereof, the said core being formed in separated sections less in number than the winding sections, 5 and means for balancing the admittances between the several line windings.

In witness whereof, I hereunto subscribe

my name this 11th day of September, A.D. 1914.

STANLEY B. KENT.
